UNITED STATES PATENT OFFICE.

CHARLES G. CANFIELD, OF CLEVELAND, OHIO.

INCLOSURE FOR BUILDINGS IN COURSE OF CONSTRUCTION.

SPECIFICATION forming part of Letters Patent No. 746,789, dated December 15, 1903.

Application filed October 18, 1902. Renewed June 25, 1903. Serial No. 163,121. (No model.)

To all whom it may concern:

Be it known that I, CHARLES G. CANFIELD, of Cleveland, in the county of Cuyahoga, State of Ohio, have invented certain new and useful Improvements in Inclosures for Buildings in Course of Construction; and I do hereby declare the following to be a full, clear, and exact description of the same, reference being had to the accompanying drawing, forming a part of this specification, and to the letters of reference marked thereon.

The object of this invention is to provide a practical and inexpensive means whereby building operations, and particularly the building of walls and partitions of cement or artificial stone, may be carried forward regardless of the weather conditions at the time; to which ends the invention consists in a portable flexible inclosure of such construction that it may be placed around and over that portion of the building under construction, the inclosure being preferably formed of canvas or woven material of such nature as to transmit sufficient light and at the same time be water-repellant and of sufficient density as to retain heat should the building operations be carried on when the temperature is low.

The accompanying drawing is a vertical section through a portion of a building in course of erection with the improved means for inclosing the working area in position.

In said drawing the wall A, which is in course of erection, is shown as having progressed to a point beyond one of the floors B of the building, which floors are preferably put in place as their level is reached. A skeleton framing, consisting of uprights C and riders and beams c, which latter may be and preferably are the floor-beams of the next story, is erected in advance of the wall construction, such skeleton framing constituting the support for the inclosure and is completed always in advance of the wall construction.

The wall illustrated is of cement or artificial stone molded *in situ*, for which purpose molds formed of mold-boards D and core-pieces D' are employed, the mold-boards being held in place by clamps D² and supported from hangers E, clamped to the skeleton framing. The hangers E also serve to support the curtain or side wall F of the inclosure and for

this purpose are extended some distance beyond the plane of the wall, whereby the curtain or inclosure wall will hang clear and out 55 of the way of the building operations. The upper edge of the curtain-wall is detachably secured to the skeleton framing by hooks or fastening devices f, while its lower edge is drawn in close to the wall by a draw-rope, as 60 shown at f'. This curtain is extended entirely around the building or that portion in course of erection, and it is preferably formed of canvas or woven material coated or impregnated with a waterproof or water-repellant substance which will facilitate the transmission of light—as, for instance, flexible varnish or oil.

To close in the top or provide a roof for the working space, the cross-beams c are utilized 70 as supports for flexible covers H, preferably one for each beam and sloping away on each side of the beam. The lower edges of the covers terminate in troughs K, which may be suspended from the edges of the covers by 75 having hooks k on the inner sides of the troughs passed through openings or eyelets in the edges of the covers, as will be readily understood from the drawing.

The drip from the troughs may be led away 80 to any suitable discharge, or the troughs may be extended to discharge at some point beyond the building-walls where it can do no injury.

With a structure such as described it is obvious 85 that the building operations may be carried on regardless of the weather, as rain or snow is excluded, and, if desired, artificial heat may be supplied to warm the inclosed area, especially if the floors are laid as the 90 work progresses. When it becomes necessary to raise the inclosing curtain, it may be readily accomplished by first shifting the hangers to the higher point and then attaching the mold-board-supporting ropes or other ropes 95 running over pulleys on the hangers to the upper portion of the curtain and then hoisting the whole into its new position.

The building operations are carried on entirely from the inside of the building, and the 100 walls as they progress incorporate the vertical portions of the skeleton frame, and thus while said frame is utilized to support the temporary inclosure it ultimately becomes a

part of the building and does not increase the expense of the building nor the labor of construction, as such framing can be run in advance of the walls with the same facility that it can be run simultaneously therewith.

Having thus described my invention, what I claim as new, and desire to secure by Letters Patent, is—

1. In an inclosure for the building area during the erection of walls of buildings, the combination with the skeleton frame extending above the walls of the building, of a flexible inclosing curtain supported from said framing around the building area and means for holding the lower edge of said curtain close to the outer side of the completed portion of the wall; substantially as described.

2. In an inclosure for the building area during the erection of walls of buildings, the combination with the skeleton frame extending above the walls of the building, of hangers carried by said framing, a flexible inclosing curtain suspended therefrom around the building area and outside of the plane of the walls, and means for holding the lower edge of the curtain close to the outer side of the completed portion of the wall; substantially as described.

3. In an inclosure for the building area during the erection of walls of buildings, the combination with the skeleton frame extending above the walls of the building, of a flexible inclosing curtain supported from said framing around the building area outside of the

plane of the walls, means for holding the lower edge of the curtain close to the completed portion of the walls and a sectional flexible cover for said building area with drip-troughs between the sections; substantially as described.

4. In an inclosure for the building area during the erection of walls of buildings, the combination with the skeleton frame extending above the walls of the building, and embodying transverse beams, of a flexible surrounding curtain, a sectional cover of flexible material, each section being centrally supported on a beam and drip-troughs supported between the adjacent edges of the sections; substantially as described.

5. In an inclosure for the building area during the erection of the walls of buildings, the combination with the skeleton frame extending above the completed portions of the walls, and embodying vertical and transverse beams, of hangers on said frame extending beyond the plane of the walls, a flexible inclosing curtain suspended over said hangers, a rope for holding the lower edge of said curtain close to the completed portion of the wall, a sectional cover for said area constructed of flexible material, each section being supported on a cross-beam and drip-troughs supported between the sections; substantially as described.

CHARLES G. CANFIELD.
